UNITED STATES PATENT OFFICE.

FRANCIS L. McLAUGHLIN, OF MONTREAL, QUEBEC, CANADA.

SILENCING DEVICE FOR TYPEWRITERS AND THE LIKE.

Application filed August 18, 1922. Serial No. 583,065.

To all whom it may concern:

Be it known that I, FRANCIS L. McLAUGHLIN, a subject of the King of Great Britain, and resident of the city of Montreal, in the Province of Quebec and Dominion of Canada, have invented certain new and useful Improvements in Silencing Devices for Typewriters and the like, of which the following is a full, clear, and exact description.

This invention relates to improvements in means for silencing typewriters, or more properly speaking, for reducing the noise incident to the operation of typewriters, and the object of the invention is to provide a simple, inexpensive and durable device which can be applied in a moment of time to a typewriter without making any alteration or modification in the typewriter and if desired without the use of attaching means.

A further object is to provide a device which will not interfere in any way with the operation of a typewriter or with the insertion or removal of paper.

It has been ascertained that the noise incident to the operation of a typewriter arises almost exclusively in two parts of the machine. The greater part of the noise appears to arise from the operation of the escapement mechanism which is usually located at the back of the carriage. A certain and smaller amount of noise arises from the impact of the type on the platen or roll of the typewriter. Typewriters are, for the most part, used on specially constructed desks which have the effect of sounding boards and which reflect and perhaps intensify the sounds incident to operation of the escapement and attendant mechanism. Even where the nature of the furniture does not reflect or intensify the noise the sounds are reflected back from hard walls or partitions adjacent the machine.

According to the present invention there is provided a casing of suitable material adapted to enclose as much as possible of the typewriter, the casing being of course adapted to the size and shape of the machine with which it is to be used. This casing, which may or may not be attached to the typewriter or typewriter support, is provided with a thick, soft lining of suitable material such as felt, which will absorb the sound waves emanating from the typewriter. It will be understood that the word "absorb"

is used in a somewhat figurative sense as indicating that little or no reflection of sound waves occurs from the felt. A special roller or platen may also be provided for the machine to deaden the sounds due to impact of the type thereon. While the use of such a roll is preferred in combination with the device hereinafter described, it must be understood that the use of such a roll is not essential except to produce the desired silencing effect to the maximum degree. Obviously, some of the sound waves emanating from the roll are deadened by the casing but the use of such a roll reduces the production of sound and therefore cooperates with the casing in producing the final effect.

In the drawings which illustrate one embodiment of the invention suitable for use with a typewriter such as an Underwood;

Fig. 1 is a front elevation of the device and

Fig. 2 a side elevation, both showing in dotted lines a typewriter in operative position in the device.

Referring more particularly to the drawings, 11 designates the back wall of the casing which extends from the typewriter supporting surface upwardly for a suitable distance and, then curves forwardly so as to slightly overhang the rear portion of the typewriter as indicated at 12. This overhanging portion is at such height above the typewriter and has a forward projection so limited that it does not interfere with the insertion or removal of paper. The back 11 is supported by means of side wings 13, which may extend to the front edge of the typewriter frame as shown in Figure 2 and which extend upwardly from the supporting surfaces as far as possible without interfering with the movement of the typewriter carriage, as will be seen for example in Figure 1. While the wings 13 have been shown as having the maximum forward projection and height possible for the typewriter illustrated, it will be understood that they may be made much shorter and lower if desired or may be omitted altogether without departing from the spirit of the invention. While the upper edge of the wings has been shown as straight in its rear portion, it will be understood that it may be specially shaped in any suitable manner to extend the enclosure of the machine to the maximum degree. Side flanges 14 may be

provided on the back extending upwardly from the wings. These flanges will serve to support and stiffen the upper portion of the back and will also increase the effect of enclosure.

- The casing thus far described may be constructed of sheet metal or other suitable material and is preferably provided on all its edges with an inwardly turned flange 15.
- 10 The entire casing is lined with soft and preferably very porous material, designated 16, which is substantially impenetrable to sound waves and from which there will be substantially no reflection of sound waves.
- 15 A material which has been found suitable for the purpose is soft felt approximately one-half an inch thick, but the use of other materials and linings thicker or thinner than one-half an inch is contemplated. The 20 lining may be held in place exclusively by the flange 15 which projects from the body of the casing a distance substantially equal to the thickness of the lining so as to cover the edges thereof, or the lining may be 25 held by the combined action of the flanges and an adhesive substance attaching it to the casing. It will also be understood that while the use of a flange is preferred on account of the greater strength, better appearance of the device and the protection afforded to the edges of the lining, that the flange may be dispensed with. While the outer casing has been shown as of solid sheet metal, it will be understood that if desired 30 a skeleton framework only sufficient to support the lining may be used.

While the casing has been illustrated as constructed of one piece of metal by stamping, it will be understood that it may be constructed in as many pieces as desired, the 40 said pieces being connected by seaming, welding, riveting or in any other suitable manner.

The device is as illustrated preferably of a 45 size and shape to enclose as much as possible of the typewriter, with as small a clearance between the typewriter and casing as is possible in order that the device may take up a minimum of space. The forwardly 50 projecting wings 13 render the device quite stable, so that it will stand securely on a typewriter supporting surface without the use of any fastening means to connect it either to the typewriter or to the supporting 55 surface. If desired, the casing may be provided with any suitable sort of attaching means, for example, inwardly or outwardly projecting lugs 17 to be screwed to the supporting surface or to a typewriter.

60 When in use the device forms an enclosure around a typewriter which will intercept the majority of sound waves emanating from the mechanism. The soft lining affords practically no reflection of these sound waves, so that the noises noticeable adjacent

to the machine when in operation are very materially reduced. The sound waves thus intercepted at the ends and back of the machine are those arising in the escapement mechanism and key action and also a part 70 of the sound waves from the platen or roll. By combining with the device a specially constructed roll in the typewriter, the production of sound waves from this source is reduced, so that the sound waves escaping from the front and top of the machine are not only less but those intercepted at the ends and back are also less, with the result that further silencing is effected.

Having thus described my invention, what I claim is:

1. A silencing device for typewriters comprising means to intercept sound waves to be positioned close to the back and ends of a typewriter and embodying end and back members, the end members being formed to permit movement of a typewriter carriage outwardly of the vertical planes thereof, the said means being of such a character that there is substantially no reflection of sound waves therefrom.

2. A device of the class described, comprising a sound interceptor adapted to be positioned in rear of a typewriter and to extend above and forwardly over the typewriter only to such extent as will permit of ordinary operation of the typewriter without moving the interceptor.

3. A device of the class described, comprising a sound intercepting device adapted to be positioned at the rear and sides of a typewriter and close to the frame thereof, the said device being formed to permit movement of a typewriter carriage beyond the confines of the device.

4. A device of the class described, comprising a sound interceptor adapted to be positioned at the back and sides of a typewriter leaving the front and top of the typewriter exposed and freely accessible without moving the interceptor.

5. A device of the class described, comprising a sound interceptor adapted to be positioned at the back and sides of a typewriter, the upper edge of said interceptor being formed to permit movement of a typewriter carriage in operation beyond the confines of the interceptor.

6. A silencing device for typewriters comprising a casing to be positioned close to the ends of a typewriter from substantially the bottom of the carriage downwardly and close to the back of the typewriter, the casing including a support and a lining of soft material such as felt.

7. A silencing device for typewriters comprising inwardly flanged back and side plates, and a lining of soft material such as felt retained and protected at its edges by the flanges, the said plates being shaped and

designed to be positioned at the back and ends of a typewriter and to permit free movement of the typewriter carriage outwardly of the end plates.

8. A device of the class described comprising a unitary structure embodying back and end members only and adapted for association with a typewriter, the device being dimensioned to lie closely against the back

and ends of the typewriter without interference with the normal operation of the typewriter, the said device presenting an inner surface substantially impenetrable to sound waves and from which substantially no reflection of sound waves will occur.

In witness whereof, I have hereunto set my hand.

FRANCIS L. McLAUGHLIN.
